UNITED STATES PATENT OFFICE.

WILLIAM T. JAMISON, OF KANSAS CITY, MISSOURI, ASSIGNOR TO LOUIS A. GASAWAY, OF SAME PLACE.

COMBINED BOOK AND SLATE.

SPECIFICATION forming part of Letters Patent No. 440,037, dated November 4, 1890.

Application filed September 27, 1889. Serial No. 325,240. (No model.)

To all whom it may concern:

Be it known that I, WILLIAM T. JAMISON, of Kansas City, in the county of Jackson and State of Missouri, have invented certain new and useful Improvements in a Combined Book and Slate, of which the following is a full, clear, and exact description, reference being had to the accompanying drawings, forming a part of this specification.

10 My present invention is for an improvement on the patent issued to me on the 13th day of March, 1888, No. 379,469.

15 My invention consists of a combined book and slate in which the slate may be readily attached at will to the book by the user of the same, and thus avoid the purchasing of a new book by the student or other person when it is desired to have the slate in conjunction therewith; and my invention consists of features of novelty hereinafter described, and 20 pointed out in the claims.

Figure I is a plan view of my improved device. Fig. II is a transverse section taken on line II II, Fig. I. Fig. III is a detail perspective showing the manner of placing the cover on the back.

25 Referring to the drawings, 1 represents the removable book-cover with the slates 2 attached thereto. I attach one of the slates to the right-hand leaf of the book-cover, as shown in the drawings.

30 3 represents an additional slate-bearing leaf that is attached to the side of the right-hand leaf of the book-cover by means of a web 4, which allows the leaf 3 to be folded over upon the cover when the slate is not in use.

35 5 represents a book with its lids 6 7 and back 8.

40 9 represents a pocket in the right-hand leaf of the book-cover into which one of the lids of the book may be thrust, as shown in Fig. III, when it is desired to attach the cover and slate to the book. This pocket is formed by 45 making that portion of the cover double, the sections being far enough apart to admit the lid of a book through an opening 10. (See Figs. I and II.)

50 The leaves of the cover are connected to each other by the usual back or web 11. The left-hand leaf of the cover is provided with a pocket

12 for the reception of one of the lids of the book. This pocket is formed in the same manner as the pocket on the right-hand side, with the exception that the upper section 13 of the cover does not extend so great a distance from the outer edge of the cover as the section on the right-hand side does. This pocket is formed in this manner to avoid bending the 60 lids of the book back too far when it is desired to place the cover on the book, and thus obviates the danger of straining or injuring the back.

65 The section 13 has its inner side cut into a convex form 14, the center of the same being nearer the web of the back than the edges are, the advantage of the same being that the person desiring to place the cover on the book may raise the section 13 up at the center and start the lid into the pocket without 70 tearing the section where it is secured at its ends, and also guiding the lid so that it will not come in contact with the edge of the section at or near its ends. (See Fig. III.)

75 15 represents a slate-bearing leaf attached to the lower end of the left-hand leaf of the book-cover by a web 16. This leaf may also be folded in upon the cover when the slate is not in use. The slate-leaf attached to the 80 end of the book-cover leaf may be attached to the side, if desired, or the one attached to the side may be attached to the end of the leaf without departing from the spirit of my invention. In placing the cover on the book, the 85 right-hand lid is thrust into its position, as shown in Fig. III, and the left-hand lid is then bent back far enough to pass into the pocket 12. As it is impossible to place the cover on the book without first bending the lids back 90 into the position shown in Fig. III, it will be seen that the cover would remain on the book with any ordinary usage of the same.

95 By the use of my improvement I can attach a slate to any book and thus avoid the expense and trouble of having the same specially manufactured, as would be the case in using the device described in my former patent.

I claim as my invention—

100 1. As a new article of manufacture, a removable book-cover bearing a slated surface and pockets in said cover for inserting the

- lids of a book, one of said pockets extending substantially the full width of one of the leaves of the cover, and the other pocket extending substantially one-half of the width of the other leaf of the cover, substantially as described, and for the purpose set forth.
2. As a new article of manufacture, a removable book-cover bearing a slated surface, and pockets in said cover for inserting the lids of a book, one of said pockets extending a portion of the width of one of the leaves of the cover, and having the section 13 over the pocket in a convex form, in order that the lid of the book may be readily entered into said pocket, substantially as described, and for the purpose set forth.

3. In a combined book and slate, the combination of the book 5, having lids 6 7, a removable cover 1, having slate-bearing leaves 3 and 15, pockets 9 and 12 in said cover, and a section 13 over one of said pockets, having its inner edge cut in a convex form, substantially as described, and for the purpose set forth.

4. A book-cover consisting of a back 11, a pocket 9, having a slate, web 4, leaf 3, having a slate, a pocket-section 13, web 16, and leaf 15, having a slate, substantially as described.

WILLIAM T. JAMISON.
